PACKAGING CONTAINER FOR SPARK PLUGS
OR THE LIKE

Robert Joseph Martini, Lyon, France, assignor to Rhone Poulenc S.A.

Filed Oct. 10, 1966, Ser. No. 4,222

Term of patent 14 years

(Cl. D9—189)

FIGURE 1 is a front perspective view of a packaging container for spark plugs or the like showing my new design;

FIG. 3 is a section as viewed along line 3—3 of FIG. 1;

FIG. 4 is a section as viewed along line 4—4 of FIG. 1.

The dominant features of the design reside in the full line portions of the drawing, the broken line showing of the spark plug in FIGURE 4 being for illustrative purposes only.

I claim:

The ornamental design for a packaging container for spark plugs or the like, as shown and described.
